UNITED STATES PATENT OFFICE

135,586

DESIGN FOR A HAT OR SIMILAR ARTICLE

Meta Merkent, New York, N. Y.

Application April 30, 1942, Serial No. 106,754

Term of patent 7 years

To all whom it may concern:

Be it known that I, Meta Merkent, a citizen of the United States, residing in the city, county, and State of New York, have invented a new, original, and ornamental Design for a Hat or Similar Article, of which the following is a specification, reference being had to the accompanying drawing, forming part thereof.

I claim:

The ornamental design for a hat or similar article, as shown.

META MERKENT.
